(57) **CLAIM**

The ornamental design for a LED light with clamp, as shown
and described.

DESCRIPTION

FIG. 1 is a front bottom left side perspective view for a LED
light with clamp, showing our new design with the hook in
extended position and clamp in non-rotated position;
FIG. 2 is a front elevational view of FIG. 1 thereof;
FIG. 3 is a rear elevational view of FIG. 1 thereof;
FIG. 4 is a left side elevational view of FIG. 1 thereof;
FIG. 5 is a right side elevational view of FIG. 1 thereof;
FIG. 6 is a top perspective view of FIG. 1 thereof;
FIG. 7 is a bottom perspective view of FIG. 1 thereof;
FIG. 8 is a front bottom left side perspective view of FIG.
1 thereof, showing the hook in folded position and clamp
in non-rotated position; and,
FIG. 9 is a front bottom left side perspective view of FIG.
1 thereof, showing the hook in extended position and clamp
rotated to the front position.
The broken lines indicate portions of the design that form no
part of the claimed design.

1 Claim, 9 Drawing Sheets
